John Henry Stahl

UNITED STATES PATENT OFFICE

JOHN HENRY STAHL, OF EL PASO, TEXAS

BALL RACK

Application filed August 14, 1931. Serial No. 557,059.

My invention relates to improvements in ball racks for use with pocket billiard tables; and the objects of my improvement are, first to promote speed and convenience in handling the balls; second, to provide an easy and convenient means for holding balls, then releasing them into a receptacle placed therefor; third, to conserve the time and promote the convenience of players; and, fourth, to save time and effort on the part of an attendant who cares for and pours the balls from the receptacle into a triangle for spotting preparatory for the beginning of an ensuing game.

I attain these objects by the mechanism illustrated in the accompanying drawing, in which—

Figure I is a view in perspective of my invention, together with a plurality of balls, a basket to receive said balls, two rods secured to my invention and, on each of said rods, a plurality of markers to score the progress made by the players in a game. Figure II is a view in perspective showing a part of the front of my invention. Figure III is a view in perspective showing the rear of said part of my invention.

Similar numerals refer to similar parts throughout the several views.

Making further reference to said drawing, the numerals 1—2—28—29—19—30 indicate the frame proper of my invention; the numerals 1a—2a indicate supporting upright ends secured to parts 1—2 of said frame; the numeral 3 is a top cross piece extending between and secured to said supporting upright ends 1a—2a; the numerals 4—4—4—4, the back which extends from end to end and from top to bottom; 5—6, rods upon which pluralities of markers are suspended; 7—8, the markers; 9—10, cleats to support said rods 5—6; 11—12—13—14, screws that secure said cleats 9—10 to parts 1—2 of the frame; 15—16—17—18, nuts that secure said rods 5—6 and prevent them from slipping out of cleats 9—10; 19, a lateral part of frame extending between and secured to parts 1—2 of the frame; 20—21—22—23, inclined runways or shelves for balls; 24—25—26—27, pluralities of balls in said inclined runways

or shelves 20—21—22—23; 28—29, central supporting parts of the frame; 30, a cross piece at the bottom extending between and secured to parts 1—2 of the frame; 31, a ball stop and release member; 32, an offset on said ball stop and release member 31; 33, a basket supporting member; 34, a basket; and 35—36, bails by means of which said basket 34 may be lifted and carried.

The numerals 19 in Figure II indicate a fragmentary part of the lateral part of frame indicated by like numerals in Figure I; the numerals 28—29 indicate central supporting parts of the frame; 31, the ball stop and release member; 32, the offset on said ball stop and release member 31; 33, the basket supporting member; and 30, a fragmentary part of the cross piece at the bottom extending between and secured to parts 1—2 of the frame.

The numerals 19 in Figure III indicate a rear view of the lateral part of frame indicated by like numerals in Figure I; the numerals 28—29 indicate the central supporting parts of the frame; the numerals 30, a rear view of the fragmentary part of the cross piece at the bottom that extends between and is secured to parts 1—2 of the frame; 31, a rear view of the ball stop and release member 31; 32, the offset on said ball stop and release member 31; 33, the basket supporting member; 37, a cleat for off-setting a spring hinge; 38, the spring hinge; and 39, the base of said ball stop and release member 31.

I am aware that there are other ball racks, but I am not aware of any other ball rack that has inclined runways or shelves wherein placed balls have a natural tendency to roll downward only to have such tendency arrested by a ball stop and release member and a base thereof, which, when permitted to move out of the way of said balls, permit them to indulge that natural tendency to fall and so fall into a receptacle, such as a basket or the like, placed underneath for the purpose of receiving said balls. These features, therefore, I desire particularly to emphasize as new and obviously useful improvements. There may be more or fewer inclined runways or shelves

than the number that appear on the drawing. Designs of my invention may be made to harmonize with tables.

It will be seen readily that so long as the bail 35 of basket 34 lies within the grooved path of the basket supporting member 33, the ball stop and release member 31 will be in the path of balls 24—25 and that the base 39 of said member 31 will be in the path of balls 26—27 and thus arrest the tendencies of the balls to fall. The openings in the inclined runways or shelves are large enough to prevent the balls from forming pyramids. Member 31 is offset at 32 to prevent the balls 24—25 from rolling behind and thus causing it to wedge against bail 35 of basket 34 and thus cause trouble when said basket 34 is to be lifted. By taking hold of the bail 36 of the basket 34 and lifting it, bail 35 will be moved from the grooved path of the basket supporting member 33 and, the pressure against the offset 32 on the ball stop and release member 31 ceasing, the said ball stop and release member 31 will be forced by the spring hinge 38 to return to its normal position out of the path of balls 24—25 and the base 39 of said member 31 will move out of the path of balls 26—27 and all of the balls will fall into the basket 34 or the like that awaits them. The balls then may be removed easily, conveniently and with less loss of time to the triangle on a billiard table for spotting in preparing for an ensuing game. In the old way, wherein balls must be retrieved from wall racks, the players are, necessarily, delayed. The base 39 of member 31 serves not only as a stop and release for balls 26—27, but also as a guide to prevent side motion as the ball stop and release member 31 moves away from and returns toward the central supporting parts 28—29 of the frame. The spring hinge 38 serves also to prevent said base 39 from becoming disengaged from between the central supporting members 28—29 when the bail 35 on basket 34 is placed in groove of the basket supporting member 33 while the inclined runways or shelves are empty. Although my invention is designed for use with tables equipped with return gulleys, it can be used also on tables not equipped with return gulleys.

The rods 5—6, the markers 7—8, the balls 24—25—26—27 and the basket 34 form no part of my invention per se and are shown on my drawing only to assist in making a full disclosure of how my invention is intended to function.

For convenience in use, my invention is to be placed at an end of a billiard table beneath the table bed level, between two of the table's legs and, preferably, by suspending my invention under the overhanging ledge of such a table by means of the top cross piece 3 inasmuch as this is convenient not only but

serves also to prevent marring the finish on the table's end.

Having described my invention, I claim and desire to protect by Letters Patent:

1. In a ball rack, the combination of a frame including supporting upright ends; cross pieces and central supporting parts disposed intermediate said ends and cross pieces; inclined runways or shelves intermediate and secured to said supporting upright ends and said central supporting parts of frame; a ball stop and release member intermediate said central supporting parts and secured by spring hinge and a cleat to that cross piece of frame next adjacent to the upper extremity of said ball stop and release member; an offset piece and a base on said ball stop and release member; a basket supporting member grooved at its top to receive the bails of a basket or the like, said basket supporting member being secured to said central supporting members and said supporting upright ends; a top cross piece extending between and secured to said supporting upright ends, and a back, substantially as described. 61
2. In a ball rack, the combination of a frame including supporting upright ends, central supporting members, cross members and a back; a ball stop and release member in said frame; a spring hinge and a cleat secured to said frame; a basket supporting member grooved to receive the bail of a basket or the like, and an offset piece secured to said basket-supporting member. 65
3. In a ball rack, the combination of a frame including supporting upright ends; a ball stop and release member having thereon a base and an offset piece, the said ball stop and release member being secured to said frame by a cleat and a spring hinge; a basket supporting member grooved at its top to receive the bails of a basket or the like; a plurality of inclined runways or shelves intermediate said supporting upright ends and the central supporting parts of said frame; a top cross piece extending between and secured to said supporting upright ends, and a back. 105
4. In a ball rack, inclined runways or shelves disposed between and secured at their outer extremities to supporting upright ends and at their inner extremities to the central supporting parts of a frame; a basket supporting member secured adjacent to the lower extremities of said central supporting parts and grooved at its top to receive the bails of a basket or the like; a ball stop and release member between said central supporting parts and secured to a part of said frame by a spring hinge on a cleat, an offset piece and a base on said ball stop and release member; a top cross piece secured to said supporting upright ends, and a back. 115
5. In a ball rack, the combination of a frame including supporting upright ends; a 130

cross piece at the top; a cross piece at the bottom; central supporting parts; inclined runways disposed between and secured to said supporting upright ends and said central supporting parts; a ball stop and release member intermediate said central supporting parts, secured by spring hinge and a cleat to that cross piece at the top next adjacent to the upper end of said ball stop and release member; an offset piece and a base on said ball stop and release member, and a basket supporting member.

JOHN HENRY STAHL.
